UNITED STATES PATENT OFFICE.

WILLIAM B. JONES, OF NEWBURYPORT, MASSACHUSETTS.

DESIGN FOR A HANDLE FOR SPOONS, &c.

SPECIFICATION forming part of Design No. 20,509, dated February 10, 1891.

Application filed December 19, 1890. Serial No. 375,211. Term of patent 7 years.

To all whom it may concern:

Be it known that I, WILLIAM B. JONES, a citizen of the United States, residing at Newburyport, in the county of Essex, in the State 5 of Massachusetts, have invented and produced a new and original Design for the Handle of Table-Ware, of which the following is a specification, reference being had to the accompanying drawings, forming part thereof.

10 Figure 1 shows my design as applied to the obverse of a spoon, and Fig. 2 shows the reverse.

The primary object of my design is to provide for the town of Newburyport, in the 15 State of Massachusetts, in accordance with a fashion existing at this time, a spoon or other article of table-ware as a "souvenir," sometimes so called, and in illustration of a historical fact connected with the town I have utilized

20 the well-known incident of Lord Timothy Dexter and the warming-pans.

It is a historical fact that one Timothy Dexter, living in Newburyport, and called "Lord Timothy Dexter," was told, more as a matter 25 of amusement than otherwise, that the then-used warming-pans made of copper would be apt to meet with sale in the Sandwich Islands, and consequently the said Dexter shipped a great number of warming-pans to 30 that place; but, contrary to the expectations of the people of his town, they proved to be just what the inhabitants wanted for the purposes of evaporating or treating sugar, and they were sold at a large price and quite a 35 fortune made thereon. The leading features, therefore, of my design are a representation of a man clad in Continental costume and a representation of a warming-pan, these features being shown as applied, respectively, to

the obverse and reverse of a spoon-handle for 40 illustration.

In the illustrations accompanying this description I show a spoon the handle of which is edge-beaded and end-scalloped. In the obverse the shank of the handle receives longitudinally the name "Newburyport," and the end of the handle receives the words "Lord Timothy Dexter." The representation of the man clad in Continental costume is between these words, and there is also the representation of a small dog, in accordance with the history of Timothy Dexter. The reverse contains the representation of a warming-pan.

All of the several described features of my design for handles of table-ware, excepting 55 the representations of the man and the warming-pan, may be omitted without departing from the spirit of my invention.

What I claim is—

1. The design for a handle for a spoon or 60 other table-ware, as herein shown and described.

2. In the design for a handle for a spoon or other table-ware, the front or obverse consisting of the representation of Timothy Dexter, 65 as herein shown and described.

3. In the design for a handle for a spoon or other table-ware, the back or reverse comprising a representation of Timothy Dexter's warming-pan, as herein shown and described. 70

In testimony whereof I have signed my name to this specification in the presence of two subscribing witnesses.

WILLIAM B. JONES.

Witnesses:
